JUG

Pierre J. Debs, Greensboro, N.C., assignor to Zarn, Inc.,
Reidsville, N.C., a corporation of North Carolina

Filed Feb. 26, 1968, Ser. No. 10,726

Term of patent 14 years

Int. Cl. D9—01

U.S. Cl. D9—40

FIG. 1 is an elevational view of a jug showing my new design;

FIG. 2 is an elevational view taken from the right of FIG. 1; and

FIG. 3 is a top plan view thereof;

FIG. 4 is an elevational view of a jug showing a modified form of my new design;

FIG. 5 is an elevational view looking from the left of FIG. 5; and

FIG. 6 is a top plan view thereof.

I claim:

The ornamental design for a jug, as shown and described.
